(57) **CLAIM**

The ornamental design for a canopy LED light fixture, substantially as shown and described.

DESCRIPTION

FIG. 1 is a bottom perspective view of a first embodiment of the new design;

FIG. 2 is a top perspective view of the first embodiment;

FIG. 3 is a left side view of the first embodiment;

FIG. 4 is a front view of the first embodiment;

FIG. 5 is a top view of the first embodiment;

FIG. 6 is a bottom view of the first embodiment;

FIG. 7 is a bottom perspective view of a second embodiment of the new design;

FIG. 8 is left side view of the second embodiment;

FIG. 9 is a front view of the second embodiment; and,

FIG. 10 is a bottom view of the second embodiment.

The broken lines shown in the drawings are for the purpose of illustrating portions of the article that form no part of the claimed design. For both embodiments, the right side view is identical to the left side view and the rear view is identical to the front view. Therefore, the right side view and the rear view of both embodiments are omitted. In addition, the top perspective view and top view of the second embodiment are identical to the corresponding views of the first embodiment and are therefore omitted.
